UNITED STATES PATENT OFFICE.

WILLARD L. POLLARD, OF EVANSTON, ILLINOIS.

DESIGN FOR AN AUTOMOBILE-PANEL.

59,432.

Specification for Design.

Patented Oct. 18, 1921.

Application filed August 6, 1921. Serial No. 490,417. Term of patent 14 years.

To all whom it may concern:

Be it known that I, WILLARD L. POLLARD, a citizen of the United States, residing at Evanston, in the county of Cook and State of Illinois, have invented a certain new, original, and ornamental Design for an Automobile-Panel, of which the following is a specification, reference being had to the accompanying drawing, forming a part thereof.

Figure 1 is a side elevation of an automobile panel showing my new design; and

Fig. 2 is a detail perspective view showing the junction between the door body and the glass panel, showing the glass seated in a channel, the channel being in turn seated in a channel supporting frame, this view being made, not to show the interior construction, but to bring out the general contour.

I claim:

The ornamental design for an automobile panel substantially as shown.

WILLARD L. POLLARD.
